UNITED STATES PATENT OFFICE.

WILLIAM REESE, OF CARNEGIE, PENNSYLVANIA.

CAR-COUPING.

SPECIFICATION forming part of Letters Patent No. 590,859, dated September 28, 1897.

Application filed March 19, 1897. Serial No. 628,320. (No model.)

To all whom it may concern:

Be it known that I, WILLIAM REESE, a citizen of the United States, residing at Carnegie, in the county of Allegheny and State of Pennsylvania, have invented or discovered a new and useful Improvement in Car-Couplings, of which the following is a full, clear, and exact description, reference being had to the accompanying drawings, forming part of this application, in which—

Figure 1 is a central longitudinal vertical section through a draw-head furnished with my improved locking device, the jaw being shown in elevation. Fig. 2 is a cross-sectional view taken on the line II II of Fig. 1. Fig. 3 is a plan view. Fig. 4 is a detail view in perspective of the tail of the locking-jaw in engagement with the locking-bar.

My invention relates to the class of twin-jaw couplers conforming to the Master Car Builders' standard, and has reference more particularly to the mechanism employed in locking and unlocking the tail of the swinging jaw, the construction otherwise involving no change from the well-known type of "Janney" couplers.

Referring to the drawings, 2 is the draw-head, in which is pivoted the usual swinging jaw or knuckle 3, provided with the extended tailpiece 4, made with a vertical flat face 5 on the inner side of its end, and having its outer end rounded at 6 and tapered down to a point.

The interior of the draw-head is hollow and provided with a vertical slot 7 8 in the upper and lower walls, in which is mounted the locking-bolt 9. This bolt is provided with a lateral elongated slot 10, through which passes a supporting-bolt 11, having a bearing in the draw-head, and by which the bolt 9 is suspended in position. The bolt 9 is suspended within the draw-head so as to be capable of swinging backwardly in the slot 8 and of rising upon the pin 11, as indicated in dotted lines, Fig. 1. At a point in the path of the tailpiece 4 the swinging jaw is beveled inwardly, as at 12, the extended end being correspondingly narrowed in width.

In the operation of closing the coupling the tailpiece swings around in the direction of the arrow, as indicated in Fig. 4, and the rounded end striking against the beveled face

12 will tend to throw the bolt backwardly, the tailpiece then riding underneath and raising the bolt sufficiently far to allow the tailpiece 55 to seat itself in a closed position, as indicated in Fig. 3, when the bolt will swing forwardly across the end of the tailpiece, thereby locking it securely in position. For the purpose of more securely retaining it in such locking 60 position the preponderance of weight in the back of the bolt 9 acts to force the bolt forwardly into position, as shown.

When it is desired to release the bolt from engagement with the tailpiece, it is drawn, 65 by means of a chain or lever secured to the link 13, upwardly and forwardly, raising the beveled edge 12 above the tailpiece and throwing the lower end back from engagement therewith, thereby releasing the knuckle, 70 when it may be opened, as in the act of uncoupling or in setting it ready for operation.

I am aware that couplers have been constructed provided with pivoted latches designed to engage the tailpiece of the knuckle, 75 but I believe I am the first to construct a locking-bar and mount it within the draw-head in the manner in which I have described.

My device is very simple and reliable in its operation, cheap and effective in its construction, not liable to get out of order, and is easily operated from the outside without danger of injury.

Having described my invention, what I claim is—

1. A car-coupler having a swinging jaw provided with an extended tailpiece rounded on its outer end, a locking-bolt vertically mounted in the path of the swinging tailpiece, longitudinal upper and lower slots in the draw-head with clearance for movement of the locking-bolt, a transverse elongated slot through the locking-bolt, a supporting-pin passing through the slot and the draw-head, and an inwardly downwardly beveled shoulder on 95 the front face of the locking-bolt, substantially as set forth.

2. In a car-coupler provided with a swinging jaw having an extended tailpiece rounded on its outer end; a vertical locking-bolt located in the path of the tailpiece mounted in a longitudinal slot through the upper and lower sides of the draw-head the lower slot being lengthened for clearance, provided

with a transverse elongated slot, a supporting-pin passing through the slot and the draw-head, and an inwardly-beveled shoulder on the front face of the locking-bolt, substantially as set forth.

3. In a car-coupler provided with a swinging jaw having an extended tailpiece rounded on its outer end; a vertical locking-bolt located in the path of the tailpiece mounted in 10 a longitudinal slot through the upper and lower sides of the draw-head, the lower slot being lengthened for clearance, provided

with a transverse elongated slot, a supporting-pin passing through the slot and the draw-head, and an inwardly-beveled shoulder on the front face of the locking-bolt, and means for raising and tipping backwardly the locking-bolt, substantially as set forth.

In testimony whereof I have hereunto set my hand this 2d day of January, 1897.

WILLIAM REESE.
